UNITED STATES PATENT OFFICE.

HARRY G. MOSCHERROSCH, OF APPLETON, WISCONSIN, ASSIGNOR OF ONE-THIRD TO
ALBERT B. VOIGT, OF STEVENSVILLE, WISCONSIN.

CAP.

1,175,167.

Specification of Letters Patent. Patented Mar. 14, 1916.

Application filed June 30, 1914. Serial No. 848,291.

To all whom it may concern:

Be it known that I, HARRY G. MOSCHERROSCH, a citizen of the United States, residing at Appleton, in the county of Outagamie 5 and State of Wisconsin, have invented certain new and useful Improvements in Caps, of which the following is a specification.

This invention relates to certain new and useful improvements in caps and has as its 10 primary object to provide a cap having a translucent or semi-transparent vizor adapted to form a shade for the eyes of the wearer of the cap to thus exclude an excess amount of light, while at the same time, vision may 15 be had through the vizor, and wherein the vizor is so arranged as to also provide a protection for the eyes against dust or in inclement weather.

The invention has as a further object to 20 provide a cap of this character wherein the vizor will be securely engaged with the crown of the cap, and wherein the vizor will be so secured thereto that cutting or abrasion of the adjacent portion of the fabric 25 of the crown by the adjacent edge of the vizor will be prevented.

A still further object of the invention is to provide a cap having the above set forth 30 features of construction and wherein the vizor will be so connected with the cap as to form a neat and secure juncture therewith, and wherein the adjacent portions of the crown contiguous with said juncture will be so arranged as to form a padding between 35 the inner edge of the vizor and the head of the wearer to provide a thoroughly comfortable construction.

With these and other objects in view my 40 invention will be more fully described illustrated in the accompanying drawings, and then specifically pointed out in the claims, which are attached to and form a part of this application.

In the accompanying drawings:—Figure 45 1 is a detail perspective view of my improved cap, Fig. 2 is a horizontal sectional view particularly showing the manner in which the vizor is secured to the crown of the cap, and Fig. 3 is a fragmentary sectional view of a modified form of the invention.

Corresponding and like parts are referred 50 to in the following description and indicated in all the views of the drawings by the same 55 reference characters.

Referring more particularly to the drawings, the numeral 10 indicates the crown of my improved cap which may be formed of any suitable fabric and which includes the side wall 11 and the top 12. Arranged within the crown 10 contiguous to the side wall 11 thereof is a sweat band 13 which is arranged to extend throughout the entire width of the side wall 11 and overlapping at its upper extremity, the top 12, as shown, 60 to form in effect, a lining for the said side wall. The contiguous overlapping portions of the sweatband, the top 12 and the side wall 11 are secured together preferably by a single line of stitching 14 adjacent the upper extremity of the crown, the side wall 11 being preferably turned in adjacent the 65 upper edge thereof as shown at 15 to bear against the margin of the top 12, it being noted that by such construction, the several 70 pieces of fabric forming the crown are joined together by a single line of stitching.

Adjacent its lower extremity, the side wall 11 is turned in, as shown at 16 to provide a pocket entirely inclosing a reinforcing strip 17. The reinforcing strip 17 may be of any suitable material but is preferably made from relatively thick fibrous paper, for a primary reason which will presently appear and for a further reason to provide 80 a stiffening for the free edge of the side wall 11 so that the crown 10 may be easily positioned upon the head. However, it is to be observed at this point, that in thus entirely inclosing the reinforcing strip 17, the said 85 strip will not only be thoroughly protected in the practical use of the cap, but the possibility of the displacement of the strip will be reduced to a minimum. Furthermore, 90 since the inwardly turned portion of the side wall of the crown is disposed between the reinforcing strip and the head of the wearer, said inwardly turned portion will 95 tend to prevent perspiration from gaining access to the strip to cause the deterioration 100 thereof.

The sweat band 13 adjacent its lower extremity is turned inwardly as shown at 18 to confront the reinforcing strip 17, and it will be observed that such overlapping portion 18 is of a width slightly greater than the width of said reinforcing strip as is also the overlapping portion 16 of the side wall 11, so that the upper edge of said reinforcing strip will bear between said overlapping 110

portions and the double thickness of fabric thereby provided will act to prevent the upper edge of said reinforcing strip from pressing against the head of the wearer to cause discomfort.

Arranged upon one side of the crown 10 and projecting from the lower extremity of the side wall 11 thereof is a vizor 19 which is preferably formed with an inner straight edge 20, and an outer edge which is curved toward opposite extremities of the vizor. The upper margin 21 of the vizor is interposed between the overlapping portions 16 and 18 of the side wall 11 and of the lining 13 respectively, with the inner straight edge 20 thereof, terminating medially of said overlapping portions and of the reinforcing strip 17. It will be observed that the contiguous portion of the reinforcing strip 17 20 as well as the adjacent portion of the overlapping extremity 16 of the side wall 11 provides a padding between the inner edge 20 of the vizor and the adjacent portion of the wall 11 to prevent said edge from cutting or abrading said side wall, while the contiguous portion of the overlapping extremity 18 of the lining 13 together with the adjacent portion of said lining provides a padding between the inner edge of the vizor 30 and the head of the wearer. By this arrangement, such inner edge is prevented from pressing against the forehead of the wearer to cause discomfort, while at the same time, the thickness of the fabric between the head of the wearer and the upper extremity of the vizor is not such as to form an uncomfortable bearing surface for the forehead. It will be noted that the crown of the cap is protected against wear by the inner edge 20 of the vizor and at the same 40 time a thoroughly comfortable structure is provided.

Preferably, the side wall 11 and the lining 13 are secured together adjacent their lower extremities by a single line of stitching 22 which extends therethrough and through the overlapping portions 16 and 18 thereof as well as through the reinforcing strip 17, thus binding the contiguous portions of the 50 sweat band 13 and of the crown 10 together and serving to maintain the reinforcing strip 17 in position. Attention is also called to the fact that where the line of stitching 22 traverses the vizor 19, the said line of stitching also extends through the vizor and thus connects the vizor with the crown of the cap. Obviously this is a very advantageous construction and arrangement since the several parts of the cap are connected 55 and held in operative position by but two lines of stitching, namely, the line of stitching 14 and the line of stitching 22.

The vizor 19 is preferably formed of some suitable flexible translucent or semi-transparent material, such as celluloid, which

has been colored to properly filter the light coming therethrough and it will be observed that said vizor is so arranged as to effectually shade the eyes from excess light and is also disposed so as to protect the eyes 70 in inclement weather. If desired, a series of longitudinally disposed apertures 23 may be formed in the vizor 19 adjacent the crown 10 to thus effect a proper ventilation beneath the vizor in use.

In Fig. 3 of the drawings, I have illustrated a slight modification of the invention wherein a preferably fabric binding 24 is arranged to embrace the inner margin of the vizor 19 to thus form a covering for the inner edge 20 thereof adapted to protect the adjacent portions of the side wall 11 of the crown and the sweat band 13 from abrasion by said edge, and to further provide a padding between the edge 20 of the vizor and the forehead of the wearer of the cap. While the construction shown in the preferred form of the invention is considered to be entirely efficient, still, if desired, the arrangement which I have illustrated in this 80 modified form may be employed, and it will be noted that in thus providing the binding 24, the inner edge 20 of the vizor is effectually prevented from so pressing against the forehead of the wearer of the cap as to 90 cause discomfort thereto. In this form of the invention, the several parts of the cap other than the binding 24 are constructed and arranged as above described with reference to the preferred form of the invention, 95 and a further description thereof at this point, will therefore not be given. However, it should be stated that in this modified form, the line of stitching 22 in addition to the function above described with reference 100 to the preferred form of the invention also serves the added purpose of securing the binding 24 in position upon the upper margin of the vizor 19.

Although I have indicated in describing 110 both the preferred and modified forms of the invention that a single line of stitching 14 and a single line of stitching 22 are preferably employed, still, it is to be understood that double rows of stitching may be used 115 in each instance, if preferred, and I therefore, do not wish to limit myself to the particular construction which I have illustrated in this regard, but have found that the single lines of stitching effectually serve 120 their intended purpose, while at the same time, the manufacture of the cap is simplified.

It will therefore be seen that my improved cap is very simple in construction and that I provide a cap having a vizor of such character and so arranged as to effectually shade the eyes of the wearer, and wherein the vizor is so connected to the crown of the cap that abrasion of the material forming 130

the cap by the adjacent margin of the vizor is effectually prevented while at the same time, a padding is provided between such margin and the forehead of the wearer of 5 the cap.

Having thus described my invention, what I claim and desire to secure by Letters Patent is:-

A cap including a crown having a side 10 wall inwardly turned at its lower edge to provide an overlapping portion, a fibrous reinforcing strip extending entirely around the crown and disposed within said overlapping portion to be entirely inclosed 15 thereby, a sweat band inwardly turned at

its lower edge to provide an overlapping portion confronting the overlapping portion of said side wall, a vizor having its inner margin disposed between said overlapping portions upon one side of the crown and 20 terminating medially thereof, and a binding embracing the inner margin of the vizor and providing a padding therefor.

In testimony whereof I affix my signature in presence of two witnesses.

HARRY G. MOSCHERROSCH. [L. S.]
